W. REES.

FIRE ESCAPE.

No. 276,468.

Patented Apr. 24, 1883.

WITNESSES

Chas. H. Orland.

Sam'l. J. Wallace,

INVENTOR

Wesley Rees,

UNITED STATES PATENT OFFICE.

WESLEY REES, OF MEMPHIS, MISSOURI.

FIRE-ESCAPE.

SPECIFICATION forming part of Letters Patent No. 276,468, dated April 24, 1883.

Application filed January 24, 1883. (No model.)

To all whom it may concern:

Be it known that I, WESLEY REES, a citizen of the United States, residing at Memphis, in the county of Scotland and State of Missouri, have invented certain new and useful Improvements in Fire-Escape Apparatus; and I do hereby declare that the following is a full, clear, and exact description of the same, reference being had to the annexed drawings, making a part of this specification, and to the letters and figures of reference marked thereon.

The object of my invention is to provide a ready means of escape from all burning buildings and of assisting firemen in extinguishing fires, and the same apparatus can be used, when necessary, to clean, paint, and repair the building or buildings to which it may be attached.

This fire-escape apparatus is arranged as follows:

Figure 1 represents a section of building, with iron rail A A, supported by brackets a a, extending around the building, from which is suspended an iron ladder, B B, attached to rail A A by means of iron hook or sheave case C, which contains a grooved sheave, b, to travel along said iron rail A A. Sheave-case C extends far enough below the top of rail A to insure safety. Ladder B is supplied with two wire guy-ropes, D D, by which said ladder may be moved along rail A A by operators on the ground. Ladder B is made with extension-section E E, and said extension is held by clamps F F. Cross-bar K K is to prevent ladder from turning and cramping sheave on the rail. The clamps F F are hinged clamps, securely bolted to the wall to hold ladder in place when not in use, said clamps being locked by pushing guy-ropes under catches f f, as seen in Fig. 2. Right-hand guy-ropes is held under clamp, as in Fig. 2, d.

Fig. 2 shows section of clamp F, with ladder locked in place. B represents ladder; F, clamp bearing on right-hand guy-ropes and ladder-rail. f f show catch, with left-hand guy-ropes in place to lock clamps and secure ladder firmly when not in use. G G are springbearings between ladder and wall, to hold ladder

and guys firmly and spring-clamps open when the left-hand guy-rope is drawn out from under catch f f.

Fig. 3 represents section of ladder, rail, and wall, &c., A being rail; B, ladder; C, sheave-case with groove-wheel; F, clamps; a a, brackets.

Fig. 4 represents a valuable part of the foregoing invention disconnected from ladder, and consists of an iron sheave-case with grooved wheel, similar to letter C, Fig. 1, with pulley-block H connected for wire rope I I, to which is attached a strong leather jacket or basket, for the purpose of raising or lowering persons to or from windows, thus permitting ladder to be used in other parts of building or buildings.

Fig. 5 shows section of sheave-case C, with grooved wheel b in place on rail, with projection of same extending below top of rail A far enough to prevent ladder from getting detached while being operated.

It will be readily perceived from the foregoing that in cases of alarm, by pulling sidewise guy-ropes D, the clamps are sprung open and ladder is released, the lower extension sliding down to its place. The ladder can then be drawn by guy-ropes around the building or buildings, affording immediate means of succor and escape. The sheave-case, with pulleys and basket L attached, can be carried up the ladder placed on rail, and thus relieve the ladder for use in other parts of the building or buildings.

I therefore claim—

1. The combination of track-rail A, held upon wall N, with traveling roller C, arranged to run thereon, and provided with arms K K beside the rail A.

2. The combination of a traveling ladder, connected with a building, with holding-clamps and a guy-ropes arranged to hold the ladder securely to the wall in a condition to be easily set free.

3. The combination of a traveling ladder with holding-clamps provided with springs arranged to hold it to the wall securely and so that it will not rattle in the wind.

4. The combination of a traveling ladder

with a traveling basket-holder, and with a device for holding the ladder and basket-holder together detachably.

5. The combination of a traveling ladder, connected with a track borne by a building, with a guy-rope and with hook-catches or equivalent means of holding ladder and guy-rope to the wall at a number of places when not in active use.

In testimony whereof and that I claim the above I have hereunto subscribed my name in the presence of two witnesses.

WESLEY REES.
